United States Patent Office

Des. 185,507
Patented June 16, 1959

185,507

APPLIQUE EMBLEM OR SIMILAR ARTICLE

Guy L. Noble, Chicago, Ill.

Application September 22, 1958, Serial No. 52,706

Term of patent 7 years

(Cl. D3—9)

Fig. 1

Fig. 2

Fig. 2 is a top view thereof.

Fig. 3 is an end view looking from the left of Fig. 1. The back of the article is plain and unornamented.

I claim:

The ornamental design for an applique emblem or similar article, as shown and described.
